UNITED STATES PATENT OFFICE.

EMIL G. JOHANSON, OF CHICAGO, ILLINOIS, ASSIGNOR TO THE NORLING ROTARY ENGINE COMPANY, OF PIERRE, SOUTH DAKOTA, A CORPORATION OF SOUTH DAKOTA.

VARIABLE-SPEED GEARING.

1,294,394.

Specification of Letters Patent. Patented Feb. 18, 1919.

Application filed October 1, 1917. Serial No. 194,120.

To all whom it may concern:

Be it known that I, EMIL G. JOHANSON, a subject of the King of Sweden, residing at Chicago, in the county of Cook and State of Illinois, have invented certain new and useful Improvements in Variable-Speed Gearings, of which the following is a specification.

My invention relates to variable speed transmission and has particular reference to shiftable driving shaft connections with a series of gears and the application thereof to a driving and a driven cone of intermeshing gears.

The objects of the invention are to simplify, make more durable, facilitate repairs and reduce cost of construction of this type of gearing; to provide a variable speed cone-gear in which the gears may be multiplied without thereby lessening the convenience of shifting from one gear to another or the strength of the construction; to provide a driving-shaft shift or key-pinion that is always firmly keyed to the driving shaft, and which may be placed in mesh with any of the different gears without the use of intervening bearing sleeves and the like; to obviate the weaknesses and complications of construction involved in hollow or slotted gear-driving shafts; to do away with the weakness of the sliding key or spline; to provide a construction which may be entirely incased and submerged in oil, if desired; to provide a key-gear shaft that may be quickly inserted or removed with its pinion without disturbing the gears, and to provide such other advantages of construction as will appear from the hereinafter detailed description of my invention.

With the above-named objects in view my invention consists in the novel construction, combination and arrangement of parts, all as hereinafter described in detail, illustrated in the accompanying drawing and more particularly pointed out in the appended claims.

In the drawing—

Figure 1 is an elevation of a cone gear mechanism embodying my invention.

Fig. 2 is a section taken substantially on line 2—2 of Fig. 1.

Fig. 3 is a section taken substantially on the line 3—3 of Fig. 2.

Fig. 4 is a reduced perspective view of the driving shaft with its clutch member secured thereto.

Fig. 5 is a perspective view of one of the driving gears all substantially identical except in size.

In the several views 2 represents a solid driving shaft with a key-pinion, gear-teeth, or clutch member, 3 keyed, shrunk or otherwise firmly secured thereto. The shaft 2 has a squared end 4 which engages for longitudinal movement a rectangular opening 5 in a shaft rotating member, motor coupling or motor element 6. In the latter is a bore 7 for the round portion 2 of the shaft and in which said portion 2 is longitudinally movable. The member 6 is rotatably mounted in a bearing-hub 8 on a bearing plate, standard, or upright 9. On another and similar frame member 10 is a hub 11 on which is a flange 12 to which is secured by means of screws 13, 18, a bearing sleeve, collar or bushing 14 that is held within the hub 11 and has a flange 15 secured to the flange 12 by means of said screws 13, and serves as a bearing for the shaft 2. The bearing 14 may also serve as a stuffing box gland by inserting a packing 16 between it, and the frame portion 10 and the hub 11, as shown. In the present connection the stuffing box feature is merely illustrative of the manner of confining oil to the hereinafter described gears if an oil casting is substituted for the bearing standards 9 and 10. The latter rest on a base plate 17 and are secured thereto by means of angle irons 18 and 19 fastened to the base plate 17 by screws 20 or otherwise. Between the members 9 and 10 are a series of gear-bearing members 21, 22, 23, 24, 25, 26, 27, and 28 which are substantially like the members 9 and 10, a side view of one of which is shown in Fig. 2, except as to height, terminating at the curved dotted line 29 in Fig. 2 and as shown in Fig. 3. In the upper end of each of the upright bearing plates 21 to 28 is an opening 30 into which is fitted a hub 31 (shown in perspective in Fig. 5) on each of a series of gear wheels 32 to 39 inclusive. The latter are in mesh with a solid cone of gears 40 with rings of gear teeth 41 to 48 inclusive. The cone of gears 40 is keyed to a shaft 49 having its bearings in openings 105 for the shaft 49 in the upper ends of the shaft supports 9 and 10. On one end of the shaft 49 is secured a collar 50 and on the other end is keyed a pulley 51 from which, as well as from any one of the gears 41 to 48, power may be transmitted from the cone of gears 40.

The member 6 is shown provided with a coupling disk 52 on which are laterally projecting studs 53 and 54 to which may be attached in any suitable manner a motor, or 5 the disk 52 may represent the motor itself. On the periphery of the disk is also a circle 10 of teeth 55 which may be conveniently placed in mesh with a motor gear wheel. These details may, however, be varied in numerous ways without departing from the spirit of my invention, the member 6 being, essentially, representative of the driving shaft power.

The motor element, or shaft rotating 15 member 6, is held against longitudinal movement on the hub 8 by means of a key-screw 56 which is threaded into said hub and engages a slot 57 formed on the periphery of a reduced portion 58 on the member 6, which 20 reduced portion is within the hub 8.

On each of the gear wheels 32 to 39 is an internal ring of clutch teeth 58 with either 25 of which the key-pinion 3 may be engaged by moving the shaft 2 along its axis on its bearings 58 and 59, the latter being in the gland 14. Such longitudinal movement is effected with the aid of any suitable device, such as a lever 60 fulcrumed at 61 on the base plate 17 and pivoted to one end of a 30 connecting bar 62 the other end of which is pivoted at 63 to an elbow bracket 64. The latter is pivoted on a screw 65 that is fixed relative to the shaft 2 by threaded engagement 66 or otherwise.

35 The upright bearing members 9, 10 and 21 to 28 are clamped together at the base plate 17 by means of long bolts or headed rods 67 and 68 and in the gear-spaces between said bearing members are washers or spacers 69 40 which should be slightly thicker than the gear wheels to prevent friction between the latter and their supports.

In gear arrangements analogous to the present invention the weaknesses which 45 prohibit their practical adoption are usually in the shaft connections, either because of the weakness of the connecting key, or keys, or the weakenings of the shafts made necessary to effect many forms of connection. For the 50 purpose of more clearly illustrating my invention I have omitted the ball bearings that are obviously applicable to the construction shown. As the pinion 3, or its equivalent or substitute in any form of construction for 55 the present purposes, is the part that must sustain many times the wear and strain imposed upon any of the other gear wheels or parts, its strength and the strength of its support is of prime importance. The shaft 60 2 and its clutch member may be withdrawn from the clutch teeth of the internally geared wheels in either direction by simply removing the screw 56 in the one instance or

the bearing or gland 14 in the other. The 65 squared end 4 and its similar opening 5 provide a joint between the shaft and its rotator 6 that is substantially as permanent and unbreakable as if the parts 6 and 2 were in one piece, and the rotator 6 being substantially outside of the gear mechanism its size and 70 strength is not limited like couplings within the gears or on the shaft 2. By simply removing the collar 50, gland 14 and the rods 67 and 68 the simple parts composed of the 75 wheels and their supports, together with the shaft and its pinion, may be quickly taken apart in case of necessity.

Having thus described my invention, I 80 claim as new and desire to secure by Letters Patent—

1. The combination with a shaft, of supports for said shaft, bearings for said shaft that are removably mounted in said supports, a series of driving gears which are arranged between said supports and are rotatable about the axis of said shaft, a bearing flange and an internal ring of clutch teeth on each of said driving gears, a stationary bearing for each of said bearing flanges on which each said driving gear is supported independently of its adjacent gears, a toothed clutch member keyed to said shaft, and means for moving said shaft longitudinally to couple its toothed clutch member with any of the rings of clutch teeth on said driving 95 gears.

2. The combination with a driving shaft, of bearings therefor, a series of intermediate bearings between said first mentioned bearings, a wheel, having external driving teeth 100 and internal driven clutch teeth, mounted on each of said intermediate bearings, a driving shaft movable longitudinally on the axis of said wheels, a clutch member on said shaft and movable therewith to engage the wheel 105 hub, spacers between said bearings, and means common to all of said bearings and spacers for clamping the same together as a unit.

3. The combination of a longitudinal, 110 movable driving shaft and a clutch member secured thereto, removable bearings for the shaft, supports for the bearings, a driven shaft, a cone of individual gears that are revoluble about said driving shaft and each 115 provided with a clutch portion to be engaged by the clutch member on the driving shaft, a separate bearing for each individual gear supported free of the driving shaft, and a cone of relatively fixed gears on said driven 120 shaft and meshing with said individual gears.

In testimony whereof I have hereunto signed my name.

EMIL G. JOHANSON.
